(51) LOC (10) Cl. .... **25-01**(57) **CLAIM**

(52) U.S. Cl.

The ornamental design for a tile pattern, as shown and described.

USPC ..... **D25/151; D25/138**(58) **Field of Classification Search****DESCRIPTION**

USPC 52/506.01, 506.06, 608, 612, 596, 314,

The sole FIGURE is of a tile pattern showing my new design. Thickness forms no part of the claimed design. The light grey shading does not indicate color or contour but shows the solid nature of the individual tiles in the tile pattern.

52/311.1, 311.2; D25/138, 151; 428/44,
428/45, 49, 50, 51
